United States Patent Office

Des. 227,721
Patented July 17, 1973

227,721

SECTIONAL SOFA

Howard I. Niederman, 3757 S. Ashland Ave.,
Chicago, Ill. 60609

Filed Jan. 3, 1972, Ser. No. 215,275

Term of patent 3½ years

Int. Cl. D6—01

U.S. Cl. D6—46

FIG. 1 is a front perspective view of a sectional sofa showing my new design;

FIG. 2 is a front elevational view of the three cushion section;

FIG. 3 is a front elevational view of the two cushion section;

FIG. 4 is a top plan view;

FIG. 5 is a rear elevational view of the two cushion section; and

FIG. 6 is a rear elevational view of the three cushion section thereof.

I claim:

The ornamental design for a sectional sofa, as shown.
